DETONATOR HEAD

Filed July 20, 1956

DETONATOR HEAD

Harold E. Staadt, Tulsa, Okla., and Joseph R. Hradel, Mount Pleasant, Mich., assignors to The Dow Chemical Company, Midland, Mich., a corporation of Delaware

Application July 20, 1956, Serial No. 603,205

1 Claim. (Cl. 102—20)

This invention relates to detonator heads, and particularly to detonator heads which are adapted for use with perforating guns of the type used in perforating the casing and bore hole wall of oil or gas wells or the like.

In the completion of oil or gas wells casing is often run into the well bore. Cement is then pumped down through the casing and up between the casing and well bore wall. A perforating gun, usually one having shaped explosive charges disposed along a light, frangible, usually tubular, frame, is lowered after the cement has "set," into the well bore to the depth of the desired productive formation and is detonated. The shaped charges blast holes through the casing and cement and into the well bore wall. In order to detonate all the shaped charges substantially simultaneously a length of detonable fuse, such as "Primacord," extends from a detonator head to each of the shaped charges. Normally a blasting cap, disposed in the detonator head and fired by electrical means, is utilized to detonate the "Primacord."

In most perforating guns the "Primacord" is carried within the tubular frame of the gun in order to protect the "Primacord" from fluid in the well bore. The tubular frame of the gun is coupled to the detonator head into which the end or ends of the "Primacord" extend. Because of leakage due to the high fluid pressures to which the gun is subjected and, occasionally, because of leakage induced by attack on the tubular gun frame by acid or other corrosive fluid in the well bore, either the blasting cap or the "Primacord" fails to detonate when an attempt is made to "fire" the gun. Unsuccessful detonation of the blasting cap is often attributed to the high fluid pressure to which the cap is exposed when leakage of the tubular frame members or detonator head occurs, or to the shorting out of the electrical firing circuit due to the presence of electrically conducting fluid in the detonator head.

The failure of the "Primacord" to detonate when the blasting cap is fired is attributed to its being wetted by well bore fluids which may contain oil, acid, water, or mixtures of these fluids. The wetting of the detonable fuse tends to make the fuse less sensitive to the shock produced by a detonating blasting cap.

Accordingly, a principal object of this invention is to provide an improved head for detonating detonable fuse materials.

Another object of this invention is to provide an improved, more reliable detonator head for a well bore perforating gun.

In accordance with this invention there is provided an elongated detonator head having a sealed, fluid impervious detonation initiating compartment and a detonable fuse receiving compartment, the two compartments having a common wall, and a shaped explosive charge so disposed in the detonation initiating compartment that its directional blast, when the charge is detonated, is towards the common wall separating the two compartments.

The invention, as well as additional objects and advan-

tages thereof, will best be understood when the following detailed description is read in connection with the accompanying drawings, in which:

Fig. 1 is an elevational view of a detonator head made in accordance with this invention and disposed in a fluid filled well bore and having a perforating gun attached to the head;

Fig. 2 is an elevational view, partly in section, of the detonator head shown in Fig. 1, and

Fig. 3 is a sectional view taken along the line 3—3 of Fig. 2.

Referring to the drawings, and particularly to Fig. 1, there is shown well bore perforating apparatus, indicated generally by the numeral 10, disposed within the casing 12 of a well bore 14. The space between the casing 12 and well bore 14 is filled with cement 16. The casing 12, as shown, is filled with any fluid 18 which may be present in the well such as oil, water, brine, drilling mud, and the like during the operation of the apparatus.

The well bore perforating apparatus comprises a firing or detonating head 20 which has an elongated, generally cylindrical configuration, suspended by a metal cable 22 having a central electrical conductor 24 which is insulated from the metal strands of the cable. The cable 22 is coupled to the detonator head by means of a socket 26.

A perforating gun, indicated generally by the numeral 28, comprising a triangular frame-work composed of hollow, frangible tubes 32, is coupled to the lower end plug 34 of the detonator head by means of the threaded connectors 36, the frame-work having containers 30 (one being shown) supported thereon in which the shaped explosive charges are held.

Referring now to Figs. 2 and 3, as well as to Fig. 1, it may be seen that the body 38 of the detonator head is hollow, contains two compartments, a detonation initiating compartment 40 and a detonable fuse receiving compartment 42, separated by a partition 68, and is of generally H shaped longitudinal cross sectional configuration. The upper end 44 and lower end 46 of the body of the detonator head 20 are closed, respectively, by an upper end plug 48 and a lower end plug 34. A fluid tight seal is effected between each of the end plugs 48 and 34 and the body 38 by means of a ring sealing gasket 50a or 50b which is disposed in a groove 52a or 52b in the end plugs 48 and 34, respectively. A second groove 54a or 54b encircles the part of each end plug 48 or 34, respectively, which extends into the compartment 40 or 42, respectively. The wall of each compartment 40 and 42 contains a similar groove 56a or 56b which is aligned with the groove in the plug 48 or 34 when the particular plug is inserted into its compartment. A bore 58a, 58b extends through the wall of each compartment 40, 42 of the body section 38 and communicates with the groove 56a or 56b, respectively, in the wall of the body section 38. By driving a nail (not shown) through each of the bores 58a, 58b and along the grooves 54a, 54b and 56a, 56b the end plugs 48 and 34 are securely attached to the body section.

The lower end plug 34 contains three bores 60 which extend from the bottom plug 34 to the top end of the plug 34. All of the bores 60 open into a large central bore 62. The lower ends of each of the bores 60 are threaded to receive the connectors 36 for the tubing 32 of the gun 28.

The bores 60 permit the ends 66 of the detonable fuse, such as "Primacord," to extend through the plug 34 and into the compartment 42. A fiber centering bushing 64, disposed in the compartment 42, serves to keep the cord ends 66 centrally disposed in the compartment 42, although other centering means could be used. The bushing 64 has a central bore 67 through which the cords extend, the upper end of the bore 67 being counter-

bored to permit the ends 66 of the detonable fuse to be spread apart if desired. The outer diameter of the bushing 64 is slightly smaller than the inner diameter of the compartment 42. The bushing 64 extends from the end plug 34 almost to the common wall of partition 68 which separates compartment 40 from compartment 42.

The detonation initiating compartment 40 contains a shaped explosive charge 70 having a concave depression 72 therein, the depression 72 facing the wall or partition 68. The outer diameter of the charge 70 is slightly less than the inner diameter of the compartment 40. The upper end part 74 of the shaped charge 70 is convexly shaped.

A fiber bushing 76 having an axial bore 78 extending longitudinally thereof and having a concave depression 80 in its lower end part is disposed above the shaped charge 70. The bore 78 is counter bored from the concave depression to near the upper end 82 of the bushing 76. A blasting cap 84 is disposed in the counter bored part of the bore 78 and is pressed against the upper end of the shaped charge 70 by means of a spring 86 which is also disposed in the counter bored part of the bore 78.

A coil spring 88 extends from the lower end 90 of the upper end plug 48 to the upper end 82 of the bushing 76. Thus, the spring 88 presses downward the bushing 76 and shaped charge 70.

A pair of electrical leads 92, 94 extend upwardly from the blasting cap 84. The lead 92 is connected to a ground terminal 96 extending from the lower end 90 of the end plug 48. The lead 94 is electrically connected to the insulated conductor 24 of the cable 22.

The cable 22 extends through the socket 26 and is connected firmly to the socket by a friction fit. The socket 26, whose lower end part is threaded, is coupled to a threaded bore 98 opening onto the top 100 of the upper end plug 48. A smaller bore 101 coaxial with the bore 98, extends through the end plug 48. The central conductor 24 passes through the axial bore of a rigid bushing 102 and then through an expendable rubber gasket 104 before passing through the bore 101 and being connected, as by the soldered connection 106, for example to the lead 94.

In operation the detonator head 20 and perforating gun 28 are lowered down the well bore to the required depth. The blasting cap 84 is fired by applying an electrical potential (potential source not shown) through lead 24 to a ground connection (not shown) to the leads 92, 94. The detonation of the blasting cap 84 fires the shaped charge 70, which may be as small as a 6 gram charge, for example, whose explosive force, directed downwardly, shatters the common wall 68 separating the detonation initiating compartment 40 from the detonable fuse receiving compartment. The blast from the shaped charge 70 is directed towards the ends 66 of the "Primacord," detonating the "Primacord" and also firing the shaped charge or charges 30 of the perforating gun 28.

The blasting cap 84, being in a sealed compartment 40 separate from the "Primacord," is not subject to excessive pressures which occasionally prevail when the "Primacord" and the blasting cap 84 are in the same compartment.

ment and a leak occurs. With a detonating device made in accordance with this invention, the blasting cap 84, shaped charged 70 and the "Primacord" 66 are all fired simultaneously, without failure, even though the compartment 42 may be filled with fluid due to a leak in the tubing 32, connectors 36 or any other part of the device which communicates with the compartment 42. In other words, the "brute force" of the exploding shaped charge 70, directed towards the "Primacord," will detonate the "Primacord" 66 under all conditions to which the "Primacord" may be subjected.

We claim:

A detonator head comprising a cylindrical body member having two axially aligned compartments separated by a partition, one of said compartments being a detonation initiating compartment and the other compartment being a detonable fuse receiving compartment, said detonation initiating compartment being closed by a first end plug and said detonable fuse receiving compartment being closed by a second end plug, said first end plug having an electrical ground connector and having an axial bore extending therethrough, a cable having at least one insulated electrical conductor and a ground conductor, said cable extending into said bore, the insulating conductor passing through said bore and the ground conductor being connected to said ground connector, a shaped explosive charge having a concave surface, said charge being disposed in said detonation initiating compartment adjacent to said partition with said concave surface facing said partition, a blasting cap retaining member having an axial bore extending therethrough, said blasting cap retaining member being disposed in said detonation initiating compartment and adjacent to said shaped charge, said bore of the retaining member being counter bored, a blasting cap, said blasting cap being disposed in said counter bored part of said bore in the blasting cap retaining member, a resilient spacer element, said resilient spacer element being disposed in said detonation initiating compartment between said first end plug and blasting cap retaining member, said blasting cap having two electrical leads, one of said leads being electrically connected to said ground connector, the other of said electrical leads being electrically connected to an insulated conductor of said cable, the second end plug which closes said detonable fuse receiving compartment having fuse feed-through bores extending therethrough and communicating with the interior of said detonable fuse receiving compartment, and spacing means disposed within said detonable fuse receiving compartment for maintaining detonable fuses in generally axial alignment with respect to said shaped explosive charge in the detonation initiating compartment.
